UNITED STATES PATENT OFFICE.

WILLIAM L. STRAHLEM, OF MIDDLE POINT, OHIO.

TRAVELING CRANE.

1,262,866.

Specification of Letters Patent. Patented Apr. 16, 1918.

Application filed March 7, 1916. Serial No. 82,663.

To all whom it may concern:

Be it known that I, WILLIAM L. STRAHLEM, a citizen of the United States, residing at Middle Point, in the county of Van Wert, 5 State of Ohio, have invented certain new and useful Improvements in Traveling Cranes; and I do hereby declare the following to be a full, clear, and exact description of the invention, such as will enable others 10 skilled in the art to which it appertains to make and use the same.

The primary object of the invention is to provide a crane which is included as a part of the equipment of a power shovel or the 15 like, and is so mounted upon the frame thereof that it can be utilized to lift the track sections from the rear of the car and deposit them in position to be coupled to the track in front of the car. To this end, 20 the invention consists in the provision of a crane which is mounted at one side of the frame of the car which supports the power shovel or similar machine and can travel from end to end thereof, the frame having 25 a swinging boom whose reach permits the use of the crane for shifting track sections or for any other ordinary purpose for which such a crane may be used.

A further object of the invention is to 30 provide a traveling crane of the above mentioned character, which is of comparatively simple and inexpensive construction, which may be easily operated, which will prove thoroughly efficient for the purposes for 35 which it is designed, and which may be operated by the power source located upon the vehicle for the operation of the scoop, shovel or other mechanism thereon.

With these objects in view, together with 40 others which will appear as the description proceeds, the invention resides in the novel combination and arrangement of parts, all as will be described more fully hereinafter, illustrated in the drawings, and particularly pointed out in the claim.

The invention will be best understood by reference to the accompanying drawings, wherein:

Figure 1, is a side elevation of a conventional form of steam shovel, and illustrating the application of a traveling crane constructed in accordance with my invention,

Fig. 2, is an end view of the device shown in Fig. 1,

55 Fig. 3, is a transverse sectional view taken substantially upon the line 3-3 of Fig. 1,

Fig. 4, is an enlarged detail section taken through the improved crane employed in attaining the objects of the invention,

Fig. 5, is a sectional plan view taken on line 5-5 of Fig. 4.

Referring now more particularly to the drawings, 10 indicates a car of that type commonly used in excavating or hoisting operation to support the shovel, scoop or 15 crane for performing these functions. The car in the present instance is of that type wherein sectional track is employed for its support, and wherein it is necessary as the car advances to lift the track at the rear of 20 the car, convey the same to the forward end of the car, and deposit the same to extend the trackway in advance of the car. It is the primary object of the invention to provide a simple and efficient means for performing these track lifting, conveying and 25 depositing functions, as well as to perform other similar lifting and conveying functions.

Mounted upon each side of the car 10, to 30 extend substantially the entire length thereof, and in spaced parallel relation, are tracks 11. These tracks are preferably arranged one adjacent the top, and the other adjacent the bottom or floor portion of the 35 car. As the trackways and mechanisms upon each side of the car are identical, that upon one side only will be described. The lowermost track 11 may be formed of a suitable rail, held spaced outwardly from 40 the side of the car by suitable brackets 12. The upper track may be similarly secured adjacent the upper part of the car, and preferably in close proximity to the sides of the 45 car. The conveyer or support for the traveling crane comprises a platform or frame 13, which is provided adjacent its inner edge with spaced wheels 14 of a construction to rest upon the lower track rail 11. A traveler or trolley 15 is arranged to travel 50 upon the uppermost rail 11 and in vertical alignment with the frame or platform 13. The traveler is provided with wheels 16 mounted in spaced relation to each other, and similar to the wheels 14 of the frame 105 upon the lowermost track. Bars 17 are secured at one end to the opposite ends of the traveler 15, extending downwardly therefrom and crossed to be connected as at 18 at opposite points at the extreme free or 110 outermost ends of the frame 13. The arrangement so far described is such that

100

weight borne by the frame or platform 13 will be delivered through the bars 17 to the traveler or trolley 15, whereby such weights are equally distributed to the spaced trackways. It will also be observed that movement of the frame 13 in its trackway will be delivered through the bars 17 to the traveler 15, whereupon both will travel in unison.

10 As a motive power for the traveling platform or frame above described, the source of power upon the car utilized for operating its shovel or hoist is employed. A shaft 19 is arranged to extend transversely of the 15 car adjacent the lower portion thereof, and the projecting ends of the shaft are provided with sprocket wheels 20. A sprocket 21 is also secured to the shaft at any point suitable in its length, over which a sprocket 20 chain 22 is passed, the said chain 22 being arranged over a sprocket 23 secured upon a shaft 24 driven by a suitable motor or engine 25 upon the car.

25 As shovels or cranes of the type mentioned are driven or operated by various sources of energy, it is to be understood that the device is not necessarily confined to the use of any particular source of power, but may be with facility applied to various types of motors.

30 Sprocket wheels 26 are mounted upon suitable shaftings adjacent the opposite ends of the car 10 and preferably in alinement with the sprockets 20 upon the shaft 19, a chain 27 being passed over the sprockets 20 and 26 35 respectively; the ends of the said chain being connected to the opposite ends of the frame or platform 13. From the construction so far described, it is apparent that the power generated by the motor or engine 25 may be 40 utilized to rotate the shaft 19 whereupon the frame 13, through its connection with the chain 27, may be moved in its trackway 11, in a direction according to that of the rotation of the shaft 19. Suitable idlers 28 45 may be employed in connection with the chain 27 to take up the slack therein.

Secured to the frame or platform 13, and preferably to project upwardly therefrom is a hub member 29. This hub member provides an annular flange 30, upon which is adapted to rest a flange or rim 31 formed to project outwardly from the lower end of a socket member 32. The socket member is thus mounted for rotary movement upon the hub section 29, and a crane arm or boom 33 extends upwardly and angularly from the upper portion of the said socket member. A link 33' pivotally connects the free end of the boom 33, and the traveler 15, whereby 50 the said boom end will be supported, a rigid extension rod 15' being extended upon the traveler 15 to utilize the pivot of the link 33' over the vertical axis of the hub section 29. The arrangement also permits of swinging 55 of the boom.

To facilitate rotating of the boom 33, the flange 31 upon the socket member 32 is provided in its periphery with teeth 34, which are in mesh with a gear 35 mounted for rotation upon the frame or platform 13. A 70 crank handle 36 may be used for rotating the above described gear, and it is obvious that rotary movement of the gear 35 will be utilized to impart similar movement to the socket member 32, whereupon the crank or 75 boom arm 33 may be rotated upon the platform.

The outermost end of the boom 33 is provided with a block or groove wheel 37, over which passes a rope, cable, or chain 38 supporting at one end a block 39 for lifting a desired load, and which may be wound at its opposite end around a drum or windlass 40 mounted upon the frame 13. It will of course be understood that the windlass 40 85 may be dispensed with and the cable 38 may be operated by hand, or the windlass may be suitably geared to a power mechanism (not shown). However, a crank 41 is shown in the present instance for manipulation of 90 the windlass.

In operation, the shaft 19 is rotated in such direction as to move the frame 13 and the part carried thereby to the rear end of the car. The crank handle 36 may then be 95 operated to swing the boom 33 adjacent the rear end of the car in convenient position to secure the block carried thereby to the section of trackway which it is desired to move. The windlass 40 may then be operated to 100 lift the load carried by the sling clear of the ground, whereupon the boom may be operated to swing outwardly from the car body, and the power source 25 operated to move the frame 13 upon its track to the forward end of the car. The boom and windlass may then be operated to deposit the load in the desired position. As shown in dotted lines in Fig. 1, the chain 27 passes 105 over the sprocket 20 in such manner as to 110 impart movement of the chain 27 reverse from that of the chain upon the opposite side of the car. By this arrangement it is seen that the traveling cranes upon each side of the vehicle move in opposite directions upon 115 the rotation of the shaft 19. Obviously such arrangement enables workmen to more quickly lift, transport, and deposit the loads.

While the above description refers to a particular embodiment of the invention, I 120 am aware that the same is susceptible to various changes in the minor details of construction and arrangement of parts and I reserve to myself the right to make such changes as I may see fit without departing 125 from the spirit of the invention.

I claim:

The combination with a car, of upper and lower tracks supported upon each side of the car, a platform on each side of the car, 130

each platform having its outer end suspended from the upper track, and bearing against the lower track in horizontal relation thereto, a shaft extending across the car, a flexible driving element mounted along each of the lower tracks, means on each end of said shaft for actuating the driving elements in opposite directions, connections between each driving element and the adjacent plat-

form, a power source on the car for actuating the shaft and a hoisting mechanism on each of the platforms.

In testimony whereof, I affix my signature, in the presence of two witnesses.

WILLIAM L. STRAHEM.
